UNITED STATES PATENT OFFICE.

ALEXANDER SELKIRK, OF ALBANY, NEW YORK, ASSIGNOR TO LOUIS DANIELS, OF SAME PLACE.

DESIGN FOR BODY OF WATER FILTER OR COOLER.

SPECIFICATION forming part of Design No. 16,404, dated December 1, 1885.

Application filed August 24, 1885. Serial No. 175,255. Term of patent 14 years.

To all whom it may concern:

Be it known that I, ALEXANDER SELKIRK, a citizen of the United States, residing at Albany, in the county of Albany and State of New York, have invented and produced a new and original Design for Bodies of Water-Filters, of which the following is a specification, reference being had to the accompanying drawing, forming a part of the same and illustrating my new design.

Heretofore the bodies of water filters and coolers have been made to present the appearance of plain cylinders with unbroken plain surfaces, or the appearance of a cylinder or vessel made of wood staves and hoops, or the appearance of several unequal cylindrical panels separated from each other by beadings similar to those employed with stove-pipes.

The leading features in my design consist in three equal cylindrical panels made with like diameters and about equal extensions in their vertical direction, and arranging these panels between annular projected moldings, which are at about equal distances apart, with the middle panel separated from its neighboring ones by two of these projected annular moldings, while the lower panel appears to start from a heavy base molding, and the upper panel appears to be surmounted by a projected annular top molding, and also producing between the equal upper and lower plain panels a middle panel of the same like diameter and vertical extension as the two former, having an ornamented or decorated surface, and separated from the former by the two middle projected annular moldings.

A is the body of the water filter or cooler. B is the base molding, and C is the cover. The base molding B is made in form of an ogee, as shown. Between this base molding

and cover C are three cylindrical panels, a, a', and a'', of equal diameters and lengths of vertical extension. These panels are separated by the ring-moldings E and F, projected boldly outward from the surfaces of their neighboring panels. The molding E shows its lower and upper parts of concave shape and separated by a flat band form of surface. The molding F is made to have its members in the form of reversed ogees; and the top molding, D, surrounding upper panel, a'', is also made in the form of reversed ogees. The middle panel, a', is shown to have its surface ornamented or decorated with scrolling form of figures, with upper and lower rows of heart-shaped figures bordering the scrolling figures. The intermediate moldings, E and F, together with the base molding, B, and top molding, D, gives to these equal cylindrical panels, a a' a'', each the appearance of an individual finish and completeness, and also that of actual separation from its neighboring panel, which is not had in the appearance of filters or coolers heretofore made with annular beads raised a little from the plane of the surfaces of the panels which they separate.

What I claim is—

The design for water filters or coolers herein shown and described, the same consisting of the intermediate decorated cylindrical panel, a', above described, and the equal cylindrical panels a below and a'' above, separated therefrom by the boldly-projected annular moldings E and F, above described, base ogee-molding B, and surmounting molding D, as set forth.

ALEXANDER SELKIRK.
